UNITED STATES PATENT OFFICE.

EMILY WEAVER AND EDWARD LAWRENCE BADDELEY, OF SOUTHPORT,
ENGLAND.

DAMPING-PAD OR THE LIKE.

SPECIFICATION forming part of Letters Patent No. 662,328, dated November 20, 1900.

Application filed May 22, 1899. Serial No. 717,822. (No model.)

To all whom it may concern:

Be it known that we, EMILY WEAVER and EDWARD LAWRENCE BADDELEY, subjects of the Queen of Great Britain, residing at Southport, in the county of Lancaster, England, have invented a certain new and useful Improvement in Damping-Pads or the Like, of which the following is a specification.

This invention relates to improvements in damping-pads or the like, such as liquid inking-pads, for use in offices, banks, and commercial houses for damping stamps, envelops, and the like, the object of the invention being to construct a damping-pad which will remain moist a considerable length of time, even when in continuous use, as is the case in a post-office or public institution, where with damping-pads as heretofore constructed it has been necessary to renew the water-supply at very short intervals. Pads constructed according to this invention also afford great facilities for cleaning and recharging when necessary.

The invention consists of the combination of a sponge or flannel pad or roller held in a saucer or dish connected with a reservoir or vessel containing water.

Our invention is illustrated in the accompanying drawings, in which—

30 Figure 1 is a longitudinal section through the pad and reservoir. Fig. 2 is a cross-section on line $y-y$, Fig. 1. Fig. 3 is a plan with the pad-cover broken away. Fig. 4 is a view of the pad. Fig. 5 is a cross-section showing 35 the roller modification referred to, and Fig. 6 is a plan of Fig. 5.

According to our invention, which is illustrated in connection with a damping-pad, we employ a reservoir or vessel a , connecting 40 with a tray or dish b , in which latter is placed a pad of felt, flannel, sponge, or other absorbent material c . The water-space in the reservoir communicates with this tray in some suitable way, such as by apertures d , through 45 which the reservoir can also be filled, though it may also be filled through a suitable opening closed by a plug, cap, or the like. In the case shown there are two apertures d , one serving for filling and the other for the escape 50 of air while the water is being run in. The

sides of the tray b are straight for a short distance, as at e , and are then flared outwardly, as at f , to prevent the felt or the like from touching the sides all the way up. This prevents the pad getting too wet, but serves to 55 keep it in a suitable state of dampness. With straight sides touching the pad all the way the capillary attraction will cause the water to be drawn fully up to the top surface of the felt with the effect of flooding it, but the arrangement described prevents this. The pad is readily removable for cleaning purposes. The dish may also be beveled directly from the bottom, the straight sides being dispensed with; but this arrangement is not so good as 65 that described.

We prefer to provide the tray with a lid g , as shown, to keep the pad clean and prevent too much evaporation, and we may also provide the top or front of the reservoir with 70 racks h for pens or the like or combine it with a calendar, inkstand, or other desk requisite.

In Figs. 5 and 6 we show an arrangement of roller c' , covered with felt or absorbent substance c^2 and revoluble by its spindle h 75 in a slot i in the flared portion f of the tray. The roller can thus be readily removed from the tray for cleaning.

What we claim is—

In a damping device, the combination with 80 a closed receptacle a of a tray b communicating therewith by apertures d through one of which the reservoir may be filled with liquid while the other acts to allow the escape of air, an absorbent material in said tray having 85 perpendicular sides, the front and side walls e of said tray rising perpendicularly for a distance and then diverging outwardly in a plane angular to said perpendicular portion to prevent contact with the absorbent material so that an excess of liquid is not taken up thereby substantially as described.

In testimony whereof we have hereunto set our hands in the presence of two subscribing witnesses.

EMILY WEAVER.

EDWARD LAWRENCE BADDELEY.
